TELEPHONE STAND WITH INDEX

Yuen Se-Kit, 46 Hoi Yuen Road, 4th Floor,
Kwun Tong, Kowloon, Hong Kong

Filed Apr. 11, 1972, Ser. No. 243,111

Claims priority, application Great Britain Oct. 14, 1971

Term of patent 14 years

Int. Cl. D14—03

U.S. Cl. D26—14 A

FIG. 1

FIG. 2

FIG. 3

FIG. 1 is a front perspective view from one side and above of the telephone stand with index showing my new design;

FIG. 2 is a rear elevation thereof; and

FIG. 3 is an elevation of the other side thereof.

I claim:

The ornamental design for a telephone stand with index, substantially as shown and described.
